(57) **CLAIM**

The ornamental design for a drawer cabinet, as shown and described.

DESCRIPTION

FIG. 1 is a perspective view of a drawer cabinet with drawer divider;

FIG. 2 is a perspective view of the drawer cabinet with drawer divider in an open condition;

FIG. 3 is a front view of the drawer cabinet with drawer divider;

FIG. 4 is a rear view of the drawer cabinet with drawer divider;

FIG. 5 is a first side view of the drawer cabinet with drawer divider;

FIG. 6 is a second side view of the drawer cabinet with drawer divider;

FIG. 7 is a top view of the drawer cabinet with drawer divider;

FIG. 8 is a bottom view of the drawer cabinet with drawer divider showing the drawer cabinet in a closed position;

FIG. 9 is a perspective view of a drawer cabinet without drawer divider;

FIG. 10 is a perspective view of the drawer cabinet without drawer divider in an open condition;

FIG. 11 is a front view of the drawer cabinet without drawer divider;

FIG. 12 is a rear view of the drawer cabinet without drawer divider;

FIG. 13 is a first side view of the drawer cabinet without drawer divider;

FIG. 14 is a second side view of the drawer cabinet without drawer divider;

FIG. 15 is a top view of the drawer cabinet without drawer divider; and,

FIG. 16 is a bottom view of the drawer cabinet without drawer divider showing the drawer cabinet in a closed position.

The broken lines shown in the drawings are for illustrative purposes only and form no part of the claimed design.
